The ornamental design for an indoor pet house, as shown and described.

DESCRIPTION

FIG. 1 is a front and right perspective view of an indoor pet house showing my new design;

FIG. 2 is a front view thereof;

FIG. 3 is a rear view thereof;

FIG. 4 is a left side view thereof;

FIG. 5 is a right side view thereof;

FIG. 6 is a top view thereof, a bottom view being omitted since the bottom view is not visible in normal use; and,

FIG. 7 is a rear and left perspective view thereof.

The broken lines in the drawings depict portions of the indoor pet house that form no part of the claimed design.
